Primary Examiner — Kelley A Donnelly(74) *Attorney, Agent, or Firm* — Kirk A. Buhler; Buhler & Associates Patenting(57) **CLAIM**

The ornamental design for a lap plate, as shown and described.

DESCRIPTION

FIG. 1 is a top perspective view of a lap plate, showing my new design in its environment;

FIG. 2 is a top plan view thereof;

FIG. 3 is a bottom view thereof;

FIG. 4 is a right-side elevation view, the left side elevation view being a mirror image thereof;

FIG. 5 is a front elevation view, the left rear elevation view being a mirror image thereof;

FIG. 6 is a cross-sectional view taken along lines 6-6 from FIG. 4 thereof;

FIG. 7 is a bottom perspective view thereof; and,

FIG. 8 is a top perspective view thereof shown in an environment of use.

The broken lines in FIGS. 1-8 depict environmental subject matter of for the invention and form no part of the claimed design.
